UNITED STATES PATENT OFFICE.

SANFORD O. ROOT, OF LODI, NEW YORK.

VICE.

SPECIFICATION forming part of Letters Patent No. 596,125, dated December 28, 1897.

Application filed September 5, 1896. Serial No. 604,974. (No model.)

To all whom it may concern:

Be it known that I, SANFORD O. ROOT, a citizen of the United States, residing at Lodi, in the county of Seneca, State of New York, 5 have invented certain new and useful Improvements in Vises, of which the following is a specification, reference being had therein to the accompanying drawings.

This invention relates to certain new and 10 useful improvements in vises, and is designed, primarily, as an improvement upon the construction shown in the Patent No. 533,946, granted to me February 5, 1895, the vise being of the same class as that shown in said 15 patent, but differing therefrom in many respects, which will be hereinafter fully explained.

The present invention has for its object, among others, to provide a suitable standard 20 for supporting the fixed jaw in lieu of having to secure it to a post or support. I dispense with the weight suspended from the pawl in my prior construction and employ a crank-shaft beneath the pawl, which crank-shaft is 25 suitably mounted in bearings on the fixed jaw and connected with the foot-lever. I provide a novel construction of lift-pin and means for actuating the same. I employ a sleeve and a cam-face as a pin for adjustment for use without 30 the lift-pin when desired. The acting face of the lever constitutes a lock, and on this lever I employ a rocking rod connected with a rocking cam for actuating the pin. I aim, further, at improvements in the details of 35 construction, whereby the device as a whole is rendered cheaper, durable and more efficient in use, capable of finer adjustment, and not liable to become damaged or to get out of order.

40 Other objects and advantages of the invention will hereinafter appear in the following description, and the novel features thereof will be particularly pointed out in the appended claims.

45 The invention is clearly illustrated in the accompanying drawings, which, together with the letters of reference marked thereon, form a part of this specification, and in which—

Figure 1 is a side elevation of my improvement with the jaws separated and a portion broken away. Fig. 2 is a top plan of the oper-

ating-lever, lift-pin, and rocking rod and cam. Fig. 3 is a section on the line 3 3 of Fig. 1, looking in the direction of the arrows. Fig. 4 is a central vertical longitudinal section 55 through the movable jaw and its accessories with a portion broken away. Fig. 5 is a detail in end elevation of the shank of the movable jaw. Fig. 6 is a detail view of the ratchet-rod and its collar and lock removed from the remainder of the vise. Fig. 7 is a perspective view of the hooked rod removed. Fig. 8 is a view of the lift-pin detached. Fig. 9 is a section on the line 9 9 of Fig. 1, looking down.

Like letters of reference indicate like parts 60 throughout the several views.

Referring now to the details of the drawings by letter, A designates the post or upright, which may be secured at its lower end in any suitable manner, as in the socket a, 70 which may rest or be fastened to the floor.

A' designates a portion of the bench to which may be secured or upon which may rest the bracket or lug a' of the fixed jaw B of the vise. This fixed jaw has a depending 75 shank B', and this shank or depending portion, as well as the shank C' of the movable jaw C, is formed hollow, with the adjacent sides of the two shanks open, as indicated, and these two shanks are connected by the 80 crossed arms D D', the upper ends of which are pivotally attached, as at d, to the shanks of said jaws in any suitable manner, and at their points of intersection the two arms are pivotally connected on a suitable pivot d'. 85 The shank B' is secured to the post or support A by suitable means, as bolts b, as indicated in Fig. 1.

E is the ratchet-rod, which may be of any requisite length and provided upon its under 90 face for a portion of its length with teeth, as seen at e, and near its outer end upon the under side it is formed with a lug or projection e', which is adapted to engage in a recess e'', formed in the boss or enlargement c' of the 95 jaw C, as shown best in Fig. 4, to prevent turning of the rod, while allowing endwise movement thereof. The other end of the rod passes through the boss or enlargement c' of the jaw B, and F is a pawl pivotally mounted, 100 as at f, within an opening f', formed at the upper end of the shank or depending portion

B' of the jaw B, as seen best in Fig. 3, the inner or acting end of the pawl working in said opening and engaging the teeth on the under side of the ratchet-rod E within the 5 enlargement or boss b', as indicated by dotted lines in Fig. 1 and as seen clearly in Fig. 3. The outer end of this pawl is weighted, as seen at f², and its under face rounded or concaved, and this under portion is engaged by 10 the horizontal portion g of the crank-shaft G, the horizontal portions of said shaft being mounted in suitable bearings g' on the bracket a' or other stationary part of the fixed jaw, and into the eyes g² at the upper ends thereof 15 are hooked or otherwise engaged the rods or links G', the lower ends of which are pivotally connected in any suitable manner with the foot-lever II, which is formed as an integral part of the foot-treadle H', the metal being bent upon itself, as at h', and the foot-lever and the treadle extending at substantially the right angle shown in Fig. 1, the rear end of the treadle being pivotally mounted, as at h', in lugs or brackets h² on the 20 upper right A. This gives to the foot-lever some resiliency and permits of the more gradual starting of the parts in their movement when the foot is placed thereupon and thus lessens the liability of injury to any of the parts. 25 H² is an arm formed with a yoke h³ at its lower end, which embraces the foot-lever and the foot-treadle, and this horizontal portion passes loosely beneath the latter, so that the foot-lever and foot-treadle have movement 30 independent thereof; but the yoke is depressed as the foot-treadle is depressed. The upper end of this arm H² is bifurcated and receives the curved arm or lever H³, pivotally mounted, as at h⁴, in an opening in the upper right A and its upper end bearing against the arm D' against its pivot, as illustrated in Fig. 1, so that slight pressure upon the foot lever or treadle will open the jaws after the pawl has been disengaged from the path of 40 the ratchet-rod, as will soon be explained. The upper end of the rod H² is pivotally connected with the curved arm H³ near its bend, as seen at h⁵ in Fig. 1.

The outer end of the ratchet-rod carries an 45 extension I in the form of a flat plate, as seen in Fig. 6, and is provided with a plurality of vertical openings i, and the connecting portion I' between this flat plate and the rod proper is also flattened, as seen in said Fig. 50 6 as well as in Fig. 4.

J is the operating cam-lever. It is bifurcated at one end, as seen best in Figs. 1 and 4, and this bifurcated end embraces the extension I of the ratchet-rod, and the bifurcation is provided with a plurality of openings j, disposed vertically through the upper and lower portions thereof in line with each other, the lever being pivotally mounted on the extension by means of a removable pin J', which 55 may be passed through either set of openings in the end of the lever and in the extension,

as occasion may require, to change the leverage and to increase the cam-surface, the cam portions of the lever acting against the outer face of a sliding collar K, the inner portion k of which is designed to slide within the sleeve K', disposed within the bore of the enlargement or boss c' of the jaw C, as seen most clearly in Fig. 4. The outer face of this sleeve K' is cam-shaped, as seen at k' in Figs. 4 and 5, while the inner face of the body portion of the collar K is cam-shaped, as seen at k² in Fig. 6. The collar K is provided with a pin K³, as seen in Figs. 1, 2, and 4, by means of which the collar can be adjusted to vary the movement of the jaw. The peculiar shape of the acting face of the operating cam-lever constitutes a lock, so that the parts will be automatically held in any of their adjusted positions. The outer face of the enlargement 85 or boss c' of the jaw C has at its upper edge an overhanging flange c², as seen in Figs. 1, 2, 4, and 5, which protects the cam-faces of the sleeve and collar, as shown.

L is a rod arranged parallel with the operating-lever, and is mounted to rock in eyes or staples or suitable means l upon the upper face of the lever, as shown. Near its outer end it is provided with the offset portion l', forming a handhold by which the rod or lever L may be rocked upon the operating-lever. This inner end is extended at right angles to its length, as seen at L', and the free end of this portion is bent at right angles to the length thereof, as seen at L², and this portion L² is passed loosely through the rocking lever M, being held by a nut m, as indicated in Figs. 1 and 2, and the other end of this lever M has projecting laterally therefrom a horizontally-disposed eye or ring M', (seen best in Fig. 4,) which engages beneath a shoulder m' of the lift-pin N, which is mounted to work in one of the openings in the bifurcated end of the operating cam-lever and adapted to bear against the outer edge of the flat extension I of the ratchet-rod, as indicated best in Fig. 2. The acting face of this pin is formed with a socket or notch N', the upper portion of which is formed with a series or notches or steps N², while its lower portion is rounded or cam-shaped, as seen at N³, the intermediate portion being straight and vertical. This pin is lifted by the rocking of the rocking rod or lever on the operating cam-lever when it is desired to open the jaws, but it automatically drops as the lever is moved around to close the jaws and forms an automatic lock to prevent opening of the jaws. It will thus be observed that by my improved construction I obtain three different adjustments—namely, that by the ratchet-bar and its engaging-pawl; second, the cam-sleeve and its co-operating cam-lever, and, third, the drop-pin just described.

O is a steel spring coiled, as shown, having one end secured by a removable pin or bolt O', held in the under side of the bifur-

cated end of the operating-lever and its other end held upon the vertical portion P' of the pin or bolt P , which is secured in the shank of the jaw C just below its boss or enlargement, as seen best in Fig. 4.

It is often desirable when not using the vise to have the lever J thrown up into a vertical or other position, so as to be out of the way. For this purpose I provide a locking bolt, 10 latch, or pin c^x , removably inserted through a fixed portion of the vise, as the jaw C , (see Fig. 4,) and into one of a series of holes or depressions in the sleeve e^x , the sleeve having the groove or slot e^2 to receive the fin e^1 15 of the ratchet-rod E . Another change required by the purpose in view is the division of the rod P , to which one end of the spring O is secured, into two parts and a means for temporarily uniting said parts. This is accomplished by severing the rod on the diagonal lines and securing them one upon the other either by a pin or sliding collar P^x . (See 20 Figs. 4 and 7:)

It will now be seen that a severance of the 25 rod P and a disconnection of the pin or latch c^x from the sleeve e^x will permit a rotation of the ratchet-bolt, its surrounding sleeves, and of the lever J , connected with said ratchet-bolt, when the locking-pin c^x may be again 30 forced into a seat, hole, or depression in the sleeve e^x , so as to retain the parts in a position wherein the lever J will be held in a vertical or other desired plane. This modification may be required on account of the particular surroundings or by a peculiarity of the work being held in the jaws of the vise, and if the lever is to be operated in such 35 changed position all that would be necessary to do would be to provide the rod E with ratchet-teeth upon two or more sides, as will 40 be readily understood.

Modifications in detail may be resorted to without departing from the spirit of my invention or sacrificing any of its advantages.

Having thus described my invention, what 45 I claim as new, and desire to secure by Letters Patent, is—

1. The combination with the jaws and their supporting-standard, of a foot-treadle pivotally mounted on the standard and having an integral foot-lever, the ratchet-rod, its pawl, a crank-shaft arranged beneath the pawl, a connection between the crank-shaft and the foot-lever, the tail end of the pawl being weighted and curved upon its under side; 55 substantially as described.

2. The combination with the jaws and the ratchet-rod, of a pivotally-mounted pawl having a weighted tail portion, a crank-shaft having its crank arranged beneath the weighted end of the tail, a pivoted treadle, and connections between the same and the crank-shaft; substantially as described.

3. The combination with the ratchet-rod 60 and the jaws, of a pawl mounted to engage the ratchet-rod, a collar revolvably mounted

on the rod and having a cam-face, and a cam-lever acting upon said collar, as set forth.

4. The combination with the ratchet-rod and the jaws, of a pawl mounted to engage 70 the ratchet-rod, a collar revolvably mounted on the rod and having a cam-face, and a cam-lever acting upon said collar, the movable jaw having a sleeve with a cam-face adapted to coöperate with the cam-face of the collar; substantially as described. 75

5. The combination with the jaws and their crossed pivoted arms, of the ratchet-rod, its pawl, the collar revolvably mounted on the rod, and a lever having a cam portion acting 80 upon said collar and forming a lock; substantially as described.

6. In a device of the character described, a combined foot-lever and foot-treadle formed of a single piece bent between its ends, with 85 the treadle and lever extending in the same vertical plane at different angles; substantially as described.

7. In a device of the character described, a combined foot-lever and foot-treadle formed 90 of a single piece bent between its ends, with the treadle and lever extending in the same vertical plane at different angles, the foot-lever being resilient; substantially as described. 95

8. The combination with the jaws and their supporting-standard, of a combined integral treadle and foot-lever pivotally mounted on the standard, a yoke loosely receiving the treadle, a lever near their connecting portion, 100 and a curved lever pivotally mounted on the standard and pivotally connected with the upper end of the yoke; substantially as described.

9. The combination with the movable jaw 105 having an enlargement with an overhanging flange upon its outer face, of a sleeve mounted in said boss, the ratchet-rod, and a collar revolvably mounted on the rod and having a projection whereby it may be revolved; substantially as described. 110

10. The combination with the movable jaw having an enlargement, of an overhanging flange at the top, of a sleeve in said enlargement having an outer cam-face, the ratchet-rod, and a collar revolvably mounted thereon and having an inner cam-face; substantially as described. 115

11. In a device of the character described, the combination with the jaws and the ratchet-rod, of means for accomplishing three independent adjustments; substantially as described. 120

12. The combination with the jaws and the ratchet-rod, and its pawl, of an operating-lever having a cam-face and pivotally mounted on the outer end of the ratchet-rod, of a spring connecting the operating-lever with a fixed part on the movable jaw; substantially as described. 125

13. The combination with the jaws and the ratchet-rod, of an operating-lever pivotally 130

connected with the ratchet-rod and having a cam-face, a collar revolvably mounted on the rod against which the cam-face is designed to act, and a spring having one end connected 5 with the lever near its pivot, and the other end mounted on the shank of the movable jaw; substantially as described.

14. The combination with the ratchet-rod and the operating cam-lever pivotally connected therewith, of a pin mounted in an opening in the lever and engaging the face portion of the rod to which it is pivoted; substantially as described.

15. The combination with the ratchet-rod 15 having a flattened portion with rounded face, the operating-lever pivotally mounted on said portion, and a pin mounted for movement in an opening in the lever and engaging the rounded portion of the ratchet-rod; substantially as described.

16. The combination with the ratchet-rod and the lever pivotally mounted thereon, of a pin mounted for vertical movement in an opening in the lever, and a rocking rod on 25 the lever for actuating said pin; substantially as described.

17. The combination with the ratchet-rod and the operating-lever pivotally mounted thereon, of a pin mounted for vertical movement in said lever and adapted to automatically drop and lock the jaws as the lever is moved; substantially as described.

18. The combination with the ratchet-rod and the operating-lever pivotally mounted 35 thereon, of a pin mounted for vertical movement in the lever, a rocking rod on said lever, and a rocking lever connected with said rod and with said pin; substantially as described.

19. In a vise of the character described, a 40 vertically-movable pin having a portion cut

away upon oppositely-disposed inclined lines one of which is toothed, substantially as specified.

20. In a vise of the character described, a vertically-movable pin having a head to be 45 engaged by the means which moves it vertically and having between its ends a portion cut away upon oppositely-disposed inclined lines one of which is toothed and the other untoothed, substantially as and for the purpose specified.

21. In a vise of the class described, the combination with the ratchet-rod and the pivotally-mounted lever, of a pin mounted for vertical movement in the lever and having a 55 portion upon one side cut away and formed with teeth upon an inclined line, and a curved portion inclined in the opposite direction; substantially as described.

22. The combination with the movable jaw 60 and the ratchet-rod, of the operating-lever pivotally mounted on said rod, and a spring having one end connected with the lever and the other end secured to a pin projecting from the shank of said movable jaw; substantially as described.

23. The combination with the movable and fixed jaws of a vise, of a ratchet-rod, a cam-lever pivoted thereto, a sleeve surrounding the ratchet-rod and having a slot for the pin 70 of said rod, and a locking pin or latch for maintaining the parts in relatively different operative connections; substantially as described.

In testimony whereof I affix my signature 75 in presence of two witnesses.

SANFORD O. ROOT.
